UNITED STATES PATENT OFFICE.

ISIDOR ROTH, OF BROOKLYN, NEW YORK, ASSIGNOR TO BENJAMIN & JOHNES, A CORPORATION OF NEW JERSEY.

BRASSIÈRE.

Application filed February 11, 1920. Serial No. 357,948.

To all whom it may concern:

Be it known that I, ISIDOR ROTH, a citizen of the United States, and a resident of Brooklyn, in the county of Kings and State 5 of New York, have invented new and useful Improvements in Brassières, of which the following is a specification.

This invention relates in general to apparel for women, and more particularly to 10 that class of garments commonly known as brassières.

The objects of the invention are to provide a brassière especially adapted to be worn with the modern low corset, the top of which 15 when worn is substantially at the wearer's waist line; to provide a brassière of this character which will support the wearer's flesh which tends to bulge outwardly over the top of the corset, particularly in fat persons, and which bulging flesh is designated 20 in the trade as the "diaphragm" of the wearer; to enable this "diaphragm" supporting portion of the brassière to be firmly and securely attached to the wearer, and more 25 particularly to the upper part of the corset; to provide such attaching means which will not slide upward off of the corset, at the wearer's back, as in stooping or bending over; to secure a construction which at the 30 same time will permit freedom of the upper part of the brassière in such stooping or bending of the wearer; to fit the said upper part of the brassière comfortably to the bust and give the wearer the desired support, and 35 to obtain other advantages and results as may be brought out in the following description.

Referring to the accompanying drawings, in which like numerals of reference indicate 40 the same parts throughout the several views,

Figure 1 is a perspective view of a garment constructed in accordance with my invention, looking at the front thereof and 45 showing the same in position on a human figure;

Figure 2 is a similar view looking at the back of the garment;

Figure 3 is a vertical sectional view 50 through the garment as worn;

Figure 4 is a horizontal sectional view on the line 4-4 of Fig. 3;

Figure 5 is a view of the outside of the garment in an extended position; and

Figure 6 is a view similar to Fig. 5, showing the garment in a partly completed condition.

In the specific embodiment of the invention shown in said drawings, the reference numeral 1 indicates the front of the brassière, the lower portion 3 of which is adapted to overlap the top 4 of the corset 5 and support the "diaphragm" of the wearer directly thereabove, as shown in Figure 3. It will be understood that by the term "diaphragm" in the trade is meant that portion of the wearer's flesh, particularly in fat persons, which tends to bulge outwardly over the top edge of the modern low bust corsets which terminate at their tops substantially at the wearer's waist line. This bulging flesh or "diaphragm" detracts from the appearance of the wearer, but it is pressed back into place by means of my improved brassière, and particularly the low portion thereof. This lower portion 3 is preferably constructed of inelastic material which will withstand considerable tension and is preferably somewhat wider at its middle portion than at its ends, the upper edge curving downwardly from said middle 3^a to the ends 3^b; also the middle part of this lower portion 3 is preferably stiffened, as by a stay 9 at its middle and other stays 10, 10 at opposite sides thereof. To the opposite ends 3^b of the said lower portion of the brassière are secured strong elastic belt sections 7 which are of substantially the same width as the ends 3^a, 3^b and adapted to detachably connect at their ends behind 90 the wearer's back, as by means of hooks and eyes 8 or any other suitable fasteners. These belt sections lie upon the upper part of the corset at the back of the wearer, as shown in Figures 2 and 3 more especially, and give 95 the proper tension to the inelastic lower portion 3 of the front of the brassière. Furthermore, it will be understood that said elastic belt sections grip the upper part of the back of the corset sufficiently to prevent them 100 from sliding upward off said corset when the wearer stoops or bends over, and thus the brassière is at all times kept in proper relation to the corset as well as the lower "diaphragm" supporting portion 3 enabled 105 to properly perform its functions.

The upper portion of the brassière is at its front 6 preferably constructed of material

which is substantially inelastic circumferentially of the body but which will yield or stretch in an up and down direction sufficiently to conform to the bust. In making 5 this upper portion 3, preferably, the blank therefor, as shown in Figure 4, is cut away at its upper part on opposite sides of an up and down line at the front of the wearer, as at 11^b, 11^b, to form a downwardly tapering 10 dart, and then at the lower part of the dart other darts are formed extending circumferentially of the wearer, as at 11^a, 11^a. When the edges of these darts are sewed together, as shown in Figure 5, they form 15 two seams 11^c and 11^d arranged at substantially right angles to each other and radiating from the apex 3^a of the lower section 3 of the front of the garment. This construction provides the required fullness 11^e to 20 receive and fit the bust. As the garment is applied, the material in the upper section 11 will yield lengthwise of the body, and as the garment is drawn toward the back its inelasticity circumferentially will cause the 25 garment to snugly fit and conform to the bust so as to effectively support the same. This construction also ensures a smooth and 30 unwrinkled condition of the garment and consequently a neat appearing and comfortable brassière.

The back portion 2 of the upper part of the brassière is formed of any suitable substantially inelastic fabric and is made up of 35 two parts 2^a, 2^a, each of which is sewed to the upright edges of the upper part of the front of the brassière, as at 12, the two back parts being provided at their free edges with means, such as the hooks and eyes 13, for detachably securing them together at the 40 wearer's back. These parts 2^a, 2^a may be provided with stiffeners 14, and at the tops of the seams 12, 12 the upper edge of the brassière is cut away as at 15 to fit under the arms of the wearer and provided with 45 suitable shoulder straps 16.

It will be noted that the elastic straps or belt sections 7 are free from the back portions 2^a, 2^a of the upper part of the brassière, as clearly shown in the drawings, and thus 50 as the wearer bends or stoops over said upper parts 2^a, 2^a may move or give up and down without disturbing the position of the lower elastic straps 7, 7 upon the top of the corset. Said elastic straps 7 therefore never become 55 dislodged from the corset, nor can the brassière as a whole become displaced with respect to the corset, and thus the lower "diaphragm" supporting portion of the brassière always retains a proper position to perform 60 its functions and secure a neat appearance and comfort to the wearer. Heretofore the only thing relied upon to secure this result has been a tape 17 with a fastener 18 adapted to engage one of the studs 19 on the front of 65 the corset, but this was at the front of the

corset and there has been nothing to keep the back from sliding up over the top of the corset as the wearer bent or stooped. By my improved construction of elastic straps 7 separated from the rest of the back of the 70 brassière, from the sides of the wearer backward, and making said straps elastic with considerable tension, as compared to the upper looser portions 2^a of the brassière, said upper and lower portions of the back of the 75 brassière operate to some extent independently and the lower elastic strap portions always retain their position upon the corset while the upper fabric portions have more 80 freedom of movement.

Obviously detail modifications and changes may be made in manufacturing my improved brassière without departing from the spirit and scope of the invention, by those skilled in the art, and I do not wish to be understood as restricting myself except as required by the following claims when construed in the light of the prior art.

Having thus described the invention, what I claim is:

1. A brassière comprising an upper portion of yielding material at the front of the garment and of inelastic material at the back of the garment and a lower diaphragm-supporting portion which is inelastic at the 95 front of the garment and connected to the upper yielding portion, the rear part of the lower portion being elastic and separate from the rear part of the upper portion of the garment.

2. A brassière comprising a lower front "diaphragm" supporting portion of unyielding material and an upper front portion of yielding material, and elastic means for connecting the ends of said lower front "diaphragm" supporting portion at the 105 back of the wearer.

3. A brassière comprising an upper front portion of material which is yielding longitudinally of the body and substantially unyielding circumferentially of the body and a lower front "diaphragm" supporting portion of unyielding material, and means for connecting said front portions at the back of the wearer, each independent of the other, the connecting means for the upper front portion being unyielding circumferentially of the body and the connecting means for the lower front "diaphragm" supporting portion being elastic.

4. A brassière comprising a lower front "diaphragm" supporting portion of unyielding material and an upper front portion secured to said lower front "diaphragm" supporting portion, and connecting means for said upper and lower front portions at the back of the wearer and independent of each other, the connecting means for the lower front "diaphragm" supporting portion being elastic.

5. A brassière comprising a lower front "diaphragm" supporting portion of unyielding material and an upper front portion of yielding material secured to said 5 lower front "diaphragm" supporting portion, and connecting means for said upper and lower front portions at the back of the wearer and independent of each other, the connecting means for the upper front portion being inelastic.
6. A brassière comprising an upper front portion of material which is yielding longitudinally of the body and substantially unyielding circumferentially of the body and 15 a lower front "diaphragm" supporting portion of unyielding material secured to said upper front portion, and connecting means for said upper and lower front portions at the back of the wearer and independent of 20 each other, the connecting means for the upper front portion being unyielding circumferentially of the body.
7. A brassière comprising a lower front "diaphragm" supporting portion of unyielding material and an upper front portion secured to said lower front "diaphragm" supporting portion, and connecting means for said upper and lower front portions at the back of the wearer and independent 25 of each other, the connecting means for the upper front portion being inelastic.
8. A brassière including a bust covering piece of material having a dart tapering 35 downwardly from the top edge thereof and opening at its small end into the meeting large ends of two other darts extending apart circumferentially of the brassière in substantial alinement with each other and at 40 substantially right angles to the first-mentioned dart, the adjacent edges formed by said darts being sewed together, and means for fastening said brassière upon the body.
9. A brassière including a body-encircling 45 band having an enlarged inverted V-shaped central portion at the front thereof, fastening means at the ends of said band for securing the band to the body, a bust-covering portion connected with said band and having a dart extending downwardly from the top edge of the bust-covering portion to the apex of the front of the said band, and other darts extending from said apex of the band in substantial alinement with each other and 50 at right angles to said first-mentioned dart, the adjacent edges formed by said darts being sewed together, and means at the side edges of said bust-covering portion for fastening the same upon the body.

ISIDOR ROTH.
